UNITED STATES PATENT OFFICE.

HEINRICH BOLTSHAUSER, OF ZURICH, SWITZERLAND.

STEAM-TURBINE-DRIVEN LOCOMOTIVE.

Application filed June 2, 1922. Serial No. 565,320.

To all whom it may concern:

Be it known that I, HEINRICH BOLTSHAUSER, a citizen of the Republic of Switzerland, residing at Zurich, Switzerland, have 5 invented certain new and useful Improvements in Steam-Turbine-Driven Locomotives, of which the following is a specification, reference being had therein to the accompanying drawing.

10 The object of the invention is to connect the surface condenser disposed in two halves longitudinally on opposite sides of the locomotive, to two turbines that drive the locomotive. One of these turbines is for ahead driving and the other a reversing or astern driving turbine, and either turbine may discharge into both halves of the condenser, thus always having a maximum condensing surface for the exhaust steam therefrom.

15 With locomotives driven by steam-turbines and provided with a surface condensing plant, the placing of the condenser causes considerable difficulties. Owing to the considerable amount of heat to be dealt 20 with and to the large amount of cooling water therefor required, the condenser has to be designed of comparatively large dimensions. However, the prescribed clearance gauge of the locomotive dare not be 25 exceeded and the overall length of the locomotive should also not be increased by the arrangement of a condenser. These difficulties have been met by providing a condenser of a cross-section that is of a tri- 30 angular shape and by arranging it below the boiler of the locomotive, said condenser being fitted with two inlet branches for the steam symmetrically disposed to the locomotive boiler. These branches have been 35 connected up by means of two conduits with two discharge branches for the steam correspondingly disposed on the turbine. How- 40 ever, a surface condensing plant of this known type is not easily accessible for the 45 purpose of inspecting and cleaning the single parts thereof. Further with respect to the dimensioning of the condenser and the placing of the requisite auxiliary devices with a plant of this type, the designer is 50 hampered by many restrictions.

The object of the present invention is to provide a surface condensing plant for locomotives driven by steam-turbines by which the aforementioned disadvantages are over- 55 come. To this end the condenser is according to the present invention provided

in two halves disposed to either side of the locomotive boiler in the longitudinal direction thereof, each of said halves being connected to a branch of the exhaust part 60 of the driving turbine.

Constructional examples of the object of the present invention are illustrated in the accompanying drawings, in which:

Fig. 1 is a side view of a steam turbine 65 driven locomotive fitted with the object of the invention.

Fig. 2 illustrates in a plan-view the embodiment of the invention in a locomotive provided with separate ahead and astern 70 turbines.

Fig. 3 shows on a slightly smaller scale a modification to the arrangement illustrated in Fig. 2.

With the constructional form illustrated 75 in Figs. 1—2, 21 and 22 denote turbines actuating by means of spur gearings 2 a lay-shaft 3, from which the transmission of power to the driving wheels 5 is effected by a parallel crank gear 4. Live steam is supplied to the turbines 21 and 22 from the steam dome of the boiler 28 of the locomotive through a conduit not shown in the drawings. The turbines 21 and 22 are further provided with an exhaust part 23, hav- 80 ing two branches 24 and 25 of which, when seen from the front, the branch 24 leads to the left and the branch 25 to the right hand side of the locomotive boiler 28. The surface condenser of the locomotive is ar- 85 ranged in two halves 26, 27 disposed to either side of the locomotive boiler 28 in the longitudinal direction thereof. To the condenser half 26 the branch 24 is connected and to the condenser half 27 the 90 branch 25 of the exhaust part 23 of the driving turbines 21 and 22 is joined. The cooling water required by the condenser halves 26, 27 is supplied from a pump 11 driven by an auxiliary turbine 12; the suction end 95 of said pump being connected up by a pipe 13 to a water collecting tank of a device not shown in the drawings, adapted to re- 100 cool the cooling water utilized in the condenser. The pump 11 discharges into a 105 conduit 29 having branches leading to the two condenser halves. The water leaves the condenser halves 9, 10 through a conduit 30 connected to the former by branches, the conduit 30 leading the cooling water back 110 into the above-mentioned collecting tank. The water of condensation is drawn from

the two condenser halves 26, 27 through the conduit 17 by means of a pump 16 driven by said auxiliary turbine 12 and is discharged into a conduit 18 leading to the boiler 28. 20 denote conduits for connecting the halves 26, 27 of the condenser to an air-pump not shown in the accompanying drawing.

The turbine arrangement is shown on a larger scale in Fig. 2, in which 21 denotes an ahead turbine and 22 an astern turbine. These turbines are connected to an exhaust steam conduit 23 common to both turbines and provided with branches 24 and 25. The condenser of this locomotive is also arranged in two halves 26, 27 disposed to either side of the locomotive boiler 28 in the longitudinal direction thereof. The condenser half 26 is connected to the branch 24 and the condenser half 27 is in connection with the branch 25 of the exhaust conduit 23.

The cooling water required by the condenser parts 26, 27 enters the latter by means of the conduit 29 and is returned by conduit 30 to the device for re-cooling the cooling water which device is not shown on the drawings.

When the ahead turbine 21 is operative the exhaust steam from the latter passes through the branch 24 into the condenser half 26 and through the middle part of the exhaust conduit 23 and the branch 25 into the condenser half 27. When, however, the astern turbine 22 drives the locomotive the exhaust steam from this turbine flows through the branch 25 directly into the condenser half 27 and through the middle part of the exhaust conduit 23 and the branch 24 into the condenser half 26.

In the modified arrangement illustrated in Fig. 3 the exhaust part of the ahead turbine 21 is directly connected by means of a conduit 24 to the condenser half 26 and the exhaust part of the astern turbine 22 is in direct connection with the condenser half 27 by means of the conduit 25. The interconnecting conduit 23 between the conduits 24 and 25 is in this arrangement connected to separate branches 21', 22' of the exhaust parts of the two turbines. Therefore when

any one of the two turbines is operative one part of the exhaust steam from the operative turbine passes through the direct connection into one condenser half and the other part of the exhaust steam passes through the interconnecting conduit 23 and through the exhaust part of the inoperative turbine into the other condenser half.

I claim:

1. A surface condensing plant for locomotives driven by steam turbines, comprising a surface condenser provided in two halves arranged on either side of the locomotive boiler in the longitudinal direction thereof, an ahead and an astern turbine, and means effecting simultaneously a connection of the exhaust parts of said turbines to both condenser-halves.

2. A surface condensing plant for locomotives driven by steam turbines, comprising a surface condenser provided in two halves arranged on either side of the locomotive boiler in the longitudinal direction thereof, an ahead and an astern turbine, means adapted to connect one of said condenser halves to the exhaust part of the ahead turbine and to connect the other of said condenser halves to the exhaust part of the astern turbine, and an interconnection between said connecting means.

3. A surface condensing plant for locomotives driven by steam turbines, comprising a surface condenser provided in two halves arranged at either side of the locomotive boiler in the longitudinal direction thereof, an ahead and an astern turbine arranged within separate casings, a conduit connecting the exhaust part of the ahead turbine to one of said condenser halves, a second conduit connecting the exhaust part of the astern turbine to the second one of said condenser halves, and a third conduit connecting the exhaust parts of the two turbines to conduct part of the exhaust of the acting turbine through said third conduit and the exhaust part of the idle turbine into the condenser half connected to the latter turbine.

In testimony whereof I affix my signature.
HEINRICH BOLTSHAUSER.
